PULP SCREEN FLOW PIPE

Emitt S. Anderson and Archie B. Haley, Kenora,
Ontario, Canada, assignors to Minnesota and
Ontario Paper Company, Minneapolis, Minn.

Application June 4, 1948, Serial No. 31,165

3 Claims. (Cl. 92—29)

1

This invention relates to flow pipes for machines which are used for screening pulp of the character produced in the paper making industry, and is more especially concerned with the pulp screening machine of the inflow type.

It is the chief object of the invention to improve flow pipes to pulp screening machines with a view to eliminating or substantially eliminating the collection of slime which normally accumulates in the type of flow inlet heretofore employed.

Other and further objects of the invention and the advantages of the same will be pointed out, hereinafter indicated in the appended claims, or will be obvious to one skilled in the art upon understanding the present disclosure.

For the purpose of this application, there has been selected to set forth one particular structure, but it is to be understood that it is here presented for illustrative purposes only and is not to be accorded any interpretation such as might have the effect of limiting what is claimed as the invention short of its true and comprehensive scope in the art.

Referring to the drawings:

Figure 1 is a cross section of the vat and tailing spout and an end view of the drum and cylindrical screen of an inflow rotary screen;

Figure 2 is a top plan view of the improved flow pipe;

Figure 3 is a sectional view through the flow pipes shown in Figure 2;

Figure 4 is a view of the single flow pipe showing one means of removably securing a closure cap thereon;

Figure 5 is a perspective view of a clip used in connection with securing the removable ends to the flow pipe;

Figure 6 is a side elevational view of the baffle; and

Figure 7 is a sectional view of the end cap.

There are several makes of what is known as an inflow rotary type screen which differ slightly in mechanical design and in other details. The type disclosed in Figure 1 is used almost entirely in connection with a paper machine where a screen is required to break up fiber bundles and to keep foreign material from reaching the paper machine. In the latter case, the pulp stock is supposed to be properly screened before being sent to the paper machine, and this type of screen shown in Figure 1 is used more as an insurance against accidents due to the presence of some foreign material that may have found its way into the prepared stock during its manipulation in the paper mill.

2

In Figure 1 is a cross sectional view of an inflow rotary screen. The principle under which this machine operates is that of gravity combined with a slight suction. The different parts include vat 10, cylinder screen 12, polygonal drum 14, tailing spout 16, and clean-out port 18. The accepted stock flows longitudinally and out one end of the apparatus. 15 indicates generally the stock inlet or flow pipes which consist of pipes 20 and 22. Pipe 20 is provided with a flanged end 24 and is the end which receives the stock from a source not shown. The opposite end of pipe 20 is closed by removable end closure 26 and is held in place by clip 28 secured to the pipe 20 and cooperating with pin 44 and bar 30 carried by the cap member 26. Pipe 20 is connected by pipes 32 and 34 to pipe 22. It is generally preferred that pipes 20 and 22 be of larger diameter than the pipes 32 and 34. By way of example, pipes 20 and 22 may be of 6" diameter and the connecting pipes 32 and 34 be of 4" diameter. Pipe 22 is provided with a removable end 42 which is secured in place similar to cap 26 of pipe 20 and the opposite end of this pipe is provided with a closed end. Pipe 22 is provided with a series of outlets 38 and generally it is preferred that members 40 be secured to the pipe at the outlets as shown in Figure 3. The end closures may be of various construction but it is generally preferred that the closure be similar to that shown in Figure 7. The end closure 26 is provided with a groove 48 to receive a sealing ring such as a rubber washer. The baffle 36 is in the form shown in Figure 6 and it may be secured in position by welding through small spaced drilled openings along the bottom and at each projection 50 on top.

In operation, the pulp from a suitable source flows through the open end of pipe 20 and through pipes 32 and 34 to outlet pipe 22. Located in outlet pipe 22 is baffle 36 to prevent surges and uneven flow through the outlet 38. The pulp flowing through outlet 38 is at sufficient flow onto the screen 12 where the tailings are removed from the acceptable stock. By the arrangement shown in Figure 2, the accumulation of slime is substantially eliminated and provides easy means for clean up. The removable ends 26 and 42 are open and the pipes can easily and quickly be cleaned by a high pressure cleaner, thus reducing the clean up time over the type of inlet flows heretofore used.

It is preferred that pipes 20 and 22 are coated with an acid and alkali resistant material such as a phenol-formaldehyde resin and then this material baked on inside and out. It is believed

that very little, if any, slime will accumulate in a pipe under pressure, and in producing this invention, the idea is to restrict the flow into the screen through a proper opening on one side so that pressure would be built up in the flow pipe. To obtain uniform distribution, it is necessary to use two pipes with a valve control on the shorter one from the main header, and have two inlets from pipe 20 to pipe 22 with a baffle in the distribution pipe 22. The arrangement obtains even distribution and increases the screen capacity. It has been found generally that only one set of flow pipes are necessary to each screen, and preferably should be located on the up-coming side of the rotating cylinder.

What is claimed as new is:

1. In a rotary pulp screen, means for delivering pulp to the screens under pressure, said means comprising a first conduit for receiving pulp, a second conduit longer than the first conduit and for receiving pulp from the first conduit and delivering the pulp through restricted passages to the pulp screen, spaced conduits of smaller size than the first and second conduits connecting the first and second conduits, a baffle in the second conduit and positioned adjacent the delivery passages and between the delivery passages and discharge end of spaced conduits connecting the first and second conduits, and removable means for closing one end of each of the first and second conduits.

2. The combination of a vat, a rotatable cylindrical pulp screen mounted in said vat, a pulp delivery means positioned above the vat and over the pulp screen, said pulp delivery means comprising two conduits of substantially the same diameter but of unequal length, two pipes of a diameter smaller than the diameter of the two conduits connecting the two said conduits, one of said conduits having pulp delivery passages therein, a baffle substantially the length of the second conduit and secured adjacent the delivery passages, each of the said conduits having a removable cover on one end, and the conduits

coated at least on the inside with an acid and alkali resisting material.

3. The combination of a vat, a rotatable cylindrical pulp screen mounted therein, a pulp delivery means positioned above the vat and over the pulp screen, said pulp delivery means comprising two conduits positioned in substantially the same horizontal plane and of substantially the same diameter but of unequal length, conduits, means of less diameter connecting the two conduits, a baffle welded to the interior of one of said conduits, said conduit having a baffle welded therein provided with pulp delivery passages located adjacent the baffle, and lip-like members secured to the conduits along the pulp delivery passages.
